UNITED STATES PATENT OFFICE.

ALBERT L. DICKINSON, OF ENGLEWOOD, NEW JERSEY.

DESIGN FOR SMOKING-PIPE.

Specification forming part of Design No. **7,949**, dated December 22, 1874; application filed November 13, 1874.
[Term of Patent 3½ years.]

To all whom it may concern:

Be it known that I, ALBERT L. DICKINSON, of Englewood, in the county of Bergen and State of New Jersey, have invented a Design for Pipe-Stem or Cigar-Holder, of which the following is a specification:

This design consists of an acorn having a side shield, from which projects the stem of the pipe. The top portion of the acorn is provided with a contraction into which the bowl of a pipe may be placed, or the design can be used simply as a cigar-holder, the tip of the cigar being placed in the upper portion of the contraction in the acorn.

The figures in the accompanying drawing illustrate a side view and an end view with the stem removed, and in which A is the stem

having a plain surface, and terminates at its lower end in a plain shield, D, and upon the face of this shield is arranged the acorn B, which is provided with a contraction, C, for the reception of a cigar or for the bowl of a pipe.

What I claim is—

The design, herein shown, consisting of the acorn B, the plain shield D, and plain stem A, as shown and described.

In testimony that I claim the foregoing I have hereunto set my hand this 5th day of November, 1874.

A. L. DICKINSON.
